METHOD OF RECOVERING DESIRABLE PETROLEUM HYDROCARBON FRACTIONS AT SUBSTANTIALLY WELLHEAD PRESSURE

Laurance S. Reid, Oklahoma City, Okla.

Application March 6, 1939. Serial No. 259,986

7 Claims. (Cl. 62—175.5)

1

This invention relates to a method of recovering desirable liquefiable hydrocarbons from the flow of high pressure natural gas wells where it is both necessary and desirable to return the residue gas to the producing formation to maintain formation pressure or to repressure a producing formation, and has for its principal object to provide for recovery of such hydrocarbons at approximately the flowing pressure of the producing well.

Under present conditions a great volume of high pressure natural gas contains profitable quantities of desirable hydrocarbons or distillate, and in order to produce and recover the desired hydrocarbon fractions, the residue gas is returned to the producing formation to prevent its waste, to conserve formation energy and to prevent condensation and subsequent loss of the desirable heavier hydrocarbon components of the reservoir fluid which inevitably results from declining pressures in gas reservoirs of the general type under consideration. Such condensation, caused by declining pressure, is commonly termed "retrograde condensation," because it is contrary to normal reactions wherein a pressure decrease is accompanied by vaporization. Processes which recover these desirable hydrocarbons have been carried on at relatively low pressures well within the normal condensation limits of these gas-liquid mixtures. To return the residue gas to the formation, it is then necessary to provide expensive compressor equipment to raise the pressure of the gas to the required injection pressure. Extensive studies of the phenomena of retrograde vaporization and condensation have resulted in process improvements which permit these hydrocarbons to be recovered at substantially high pressures, thereby greatly lowering the differential pressure between the denuded gas and the pressure required to inject the denuded gas into the producing formation. Consequently smaller and less expensive compressor equipment may be used and operated with less power consumption. The fact remains, however, that the operating pressures of these improved processes are limited by the pressure at which normal condensation ceases and retrograde vaporization takes effect, and this pressure is denoted by a maximum liquid volume condensed from a unit volume of the gaseous well flow when condensed under constant temperature conditions. This pressure may be termed "optimum liquefaction pressure." Extensive studies of the reservoir fluids produced by the numerous known gas fields

of this general type indicate that this optimum liquefaction pressure is definitely fixed by the composition of the hydrocarbon mixture comprising the reservoir fluid and that the variation in this optimum liquefaction pressure is confined, with but few exceptions, to the range of 800 to 1200 pounds per square inch. Moreover, these studies indicate that there is no relationship between the reservoir pressure and the optimum liquefaction pressure exhibited by the reservoir fluid, so that it is not uncommon to find that the gaseous flow from a well at 3500 pounds pressure exhibits an optimum liquefaction pressure of 1000 pounds per square inch. The compressor equipment incorporated into present day condensation type distillate recovery systems therefore remains exceedingly costly and requires great power consumption.

As pointed out above, I have provided a method of recovering the liquefiable hydrocarbon contents of said gaseous reservoir fluids at pressures substantially near the well head pressure, thereby greatly reducing the required compressor horsepower and cost required to return the residue gas to the producing formation.

In carrying out my invention I utilize the relationship between the composition of the reservoir fluid and the optimum liquefaction pressure cited above, and by means of admixing definite quantities of high molecular weight hydrocarbon liquid with the well stream, I alter the composition of the hydrocarbon mixture flowing into the recovery system and thereby adjust the optimum liquefaction pressure upward to that pressure which, when considered to be the pressure at the compressor suction, will permit the compressor equipment to operate at maximum efficiency and minimum compression ratio. Not only does this enable compressor equipment to deliver a maximum volume of gas per brake horsepower developed by reducing compression ratio to a minimum, but also it increases the volumetric capacity of the compressor equipment by taking greater advantage of the supercompressibility characteristics exhibited by all gases at high pressures since this deviation from the ideal gas laws increases directly with the pressure up to approximately 3000 pounds per square inch. The remainder of the process utilizes the established principles of condensation and absorption, one method of which is practiced as illustrated in the accompanying drawings, wherein:

55 Fig. 1 is a flow diagram of a high pressure

3

condensate recovery and absorption system embodying the features of my invention.

Fig. 2 is a graph showing the approximate relation between molecular weight of well fluids and the optimum liquefaction, or so-called retrograde point, which relationship has been derived from extensive tests in different high pressure gas fields of the Texas-Louisiana-Gulf area.

Referring more in detail to the drawings:

1 designates a sub-surface formation containing a petroleum hydrocarbon under high pressure and temperature, and 2 designates a producing well drilled into the formation and where-through the formation fluid is discharged in a gaseous flow containing the desirable hydrocarbon fractions. The discharge from the well is taken from the well casing 3 and/or from the well tubing 4, through branches 5 and 6 of a flow line 7, preferably without any substantial reduction in pressure, and passed through a cooler 8.

The cooler 8 may be of any suitable type; for example, a shell having a plurality of tubes for the passage of the well flow, and around which is circulated a stream of water as a cooling medium, the water being admitted through a pipe 9 and discharged through a connection 10. The discharge line 11 from the cooler is connected with a pipe 12 discharging into the base of an absorbing tower 13 through a pressure regulating valve 14.

Since the critical region, i. e., the optimum accumulation pressure, in which retrograde phenomena are observed is found to exist at progressively higher pressures as the molecular weight of the mixture of the hydrocarbons in the vapor-liquid system increases, I therefore elevate the liquefaction pressure by increasing the molecular weight of the hydrocarbon mixture through the continuous addition of definite quantities of high molecular weight hydrocarbon liquid, thereby altering the chemical and physical characteristics of the original well stream. The extent to which the optimum liquefaction pressure is elevated is dependent upon the molecular weight of the original well stream and the molecular weight and quantity of the extraneous hydrocarbon liquid that is mixed with each unit volume of the well stream. For example, a well flowing at 2800 pounds per square inch produces a fluid having molecular weight of 20.2. Referring to Fig. 2, it is seen that the optimum liquefaction pressure exhibited by this reservoir fluid is 1200 pounds per square inch and in order to reduce the compressor requirements to a minimum it is desired to process this gas at 1900 pounds per square inch in order to return the residue gas to the formation at 2850 pounds per square inch input well head pressure, representing a compression ratio of 1.5. Again referring to Fig. 2, it is seen that it will be necessary to increase the molecular weight of the well stream to 26.5 in order to obtain maximum condensation at 1900 pounds per square inch. A readily available liquid hydrocarbon is selected, for example a medium gas oil having a molecular weight of 220. A calculated material balance shows that it will be necessary to mix 2.7 gallons of this heavy hydrocarbon liquid with each thousand standard cubic feet of gaseous fluid produced from the well in order to raise the molecular weight of the mixture to 26.5. The high molecular weight liquid hydrocarbon may be either straight-run or cracked naphtha, kerosene, gas-oil, lube oil, lube distillate, topped (or skimmed)

4

crude oil, and/or crude petroleum oil. It is also possible to use refined or crude coal-tar products and similar high molecular weight hydrocarbon liquids.

The heavy molecular weight liquid selected may be obtained from any available extraneous source or it may be derived from the recovered condensate by means of fractionation. In the first instance a pipe line 15' carrying the high molecular weight liquid may be connected with the pipe 15 which carries the well stream to the absorber 13 with the volume of flow regulated in accordance with the calculated amount so that the admixture has the predetermined molecular weight of 26.5. The high molecular weight liquid is preferably thoroughly mixed with the well stream by mechanical means, such as an atomizer 16, prior to admission into the absorber. The majority of the liquid content of the mixture is separated from the gaseous phase in the absorber by means of retrograde condensation at the assumed pressure of 1900 pounds. Another stream of the high molecular weight liquid is preferably introduced through a branch line 17 leading to the upper tray 18 of the absorber column so that it descends through the respective trays of the column in counter-current flow with respect to the ascending gas stream, thereby removing any remaining desirable liquefiable components from the gaseous phase introduced through the pipe 12 and moving upwardly through that part of the absorber which contains the respective trays. The enriched liquid collects in the base of the column together with the condensate and is discharged from the absorber through a pipe 19 under control of a valve 20. Since the molecular weight of the injected hydrocarbon is sufficiently high to raise liquefaction pressure of the admixture to approximately the desired well head pressure, the denuded gas is delivered through a pipe 21 at the pressure of approximately 1900 pounds, so that only a small amount of compression is required to return the gas to the formation. The gas is, therefore, delivered to a relatively small compressor unit 22 having a discharge connected by a return line 23 leading to an injection well 24 wherethrough the gas is returned to the formation for flow toward the well 2, thereby maintaining the formation pressure, and vaporizing any recoverable liquid hydrocarbons which may exist in the formation so that they may be carried to the well 2.

In the latter instance, the heavy molecular weight liquid is obtained by fractionation of the recoverable condensate as hereinafter described, the desired fraction being admitted to the absorber through the pipes 12 and 17 to effect desired condensation. In both instances the condensed and enriched liquid is discharged from the absorber through a pipe 19 into a separator 25. When dissolved gas and/or readily vaporizable components are separated from the liquid and discharged through a line 26 under control of a pressure regulator 27, the discharge from the line 26 is collected in a suitable vessel 28 and is vented through a line 29. This vented gas may be delivered to the compressor unit for fuel purposes, processed for its natural gasoline content, compressed and injected into the formation, or otherwise suitably disposed of. The separated liquids are discharged from the base of the separator through a pilot control valve 30, by way of a pipe line 31 discharging to storage tanks 32 and 33.

When the heavy molecular weight naphtha is used a portion of the relatively stable liquid is

drawn from the storage tanks through a line 34 connected with the bottom of the storage tanks by a pump 35, circulated through a heat exchanger 36, and delivered through a pipe 37 into a fractionator tower 38.

The high molecular weight liquid is produced in the fractionator by stripping the tower bottom product to the desired initial boiling point, probably 300 to 400 degrees F., by circulating through a reboiler 39. This liquid is withdrawn continuously from the base of the fractionator tower 38 through a pipe 40, and circulated in heat exchange relation with the liquid being pumped to the fractionator. The cooled liquid is delivered from the heat exchanger through a pipe 41, passed through a refrigerating cooler 42, and delivered into the well stream through the pipe 15 and into the absorber through the branch line 17 under the pressure of a pump 43, as above described.

The overhead cut from the fractionator is passed through a pipe 44 and circulated through a condenser 45, the condensate being collected in an accumulator 46. A part of the liquid collecting in the accumulator is withdrawn through a pipe 64 by a pump 65, discharging through a pipe 66 into the top of the fractionator to reflux the vapors rising in the fractionator tower. The stock collecting in the accumulator may command the market price for light, straight run gasoline, or possibly natural gasoline, and is circulated by a pump 47 through a preheater 48, for discharge through a pipe 49 into a stabilizer column 50. In the stabilizer the bottom product is circulated through a reboiler 51, and is continuously drawn off through a line 58, passed through a heat exchanger 59, and delivered to a stabilized gasoline storage tank 60 through a line 61.

Stock from the storage tanks 32 and 33 is circulated through the heater 58 by connection therewith of a pipe 62, having connection through a line 63 with the pump 47 where the liquid is discharged to the preheater 48 and to the stabilizer. The overhead cut from the stabilizer is discharged through a pipe 67 leading from the top of the stabilizer tower, and passed through a condenser 68 from where the condensate is delivered into an accumulator 69. The condensed liquid collecting in the accumulator is recirculated through a pipe 70, under pressure of a pump 71, back into the top of the stabilizer column through a pipe 72 as reflux. The fixed gas collecting in the accumulator may be discharged through a pipe 73 under control of a pressure regulator 74, into a storage tank 75, which gas may be used for fuel or otherwise suitably disposed of.

From the foregoing it is obvious that I have provided a system wherein the desirable hydrocarbon fractions are readily separable and recoverable at the desired high pressures, so that the denuded gas may be returned to the formation for pressure maintenance purposes with a relatively small increase in pressure, and that the high molecular weight hydrocarbon is readily manufactured by fractionation of a part of the recovered hydrocarbons. It is, therefore, possible to produce condensate from high pressure subterranean formations at the highest possible pressures in order to avoid high compression ratio between the intake and discharge sides of the compressors used in returning the denuded gas to the formation.

What I claim and desire to secure by Letters Patent is:

1. The method of recovering desirable liquefiable constituents from distillate well gas initially at a pressure at least as high as a pressure within the retrograde condensation range of said constituents which comprises, expanding the gas to a pressure within the retrograde condensation range of said constituents, separating the resulting condensed constituents from the uncondensed gas, fractionating said condensed constituents into a relatively low boiling gasoline fraction and a relatively heavy liquid fraction, and contacting the expanding gas with at least a portion of said relatively heavy liquid fraction and thereby raising the normal condensation pressure of said constituents.

2. The method of recovering desirable liquefiable constituents from a distillate gas mixture having an initial pressure at least as high as a pressure within the retrograde condensation range of said mixture, which comprises contacting the distillate gas mixture with a heavy liquid hydrocarbon fraction for forming a mixture having a higher normal condensation pressure than the original gas mixture to condense said liquefiable constituents from the gas mixture, separating the resulting condensed constituents into a relatively low boiling gasoline fraction and a relatively heavy liquid fraction for forming said contacting liquid, and conveying said heavy liquid fraction to the place of contact.

3. The method of recovering desirable liquefiable constituents from a distillate gas mixture having an initial pressure at least as high as a pressure within the retrograde condensation range of said mixture, which comprises expanding the gas mixture to a pressure within the retrograde condensation range of said constituents, contacting the expanding distillate gas mixture with a relatively heavy liquid hydrocarbon fraction for forming a mixture having a higher normal condensation pressure than the original gas mixture to condense said liquefiable constituents from the gas mixture, separating the resulting condensed constituents from the residue gas, processing the resulting condensed constituents to obtain a heavy liquid hydrocarbon fraction for forming said contacting liquid, and conveying said heavy liquid fraction to the place of contact.

4. The method of recovering desirable liquefiable constituents from a distillate gas mixture having an initial pressure at least as high as a pressure within the retrograde condensation range of said mixture, which comprises contacting the distillate gas mixture while at said pressure with a relatively heavy liquid hydrocarbon fraction for forming a mixture having a higher normal condensation pressure than the original gas mixture to condense said liquefiable constituents from the gas mixture, separating the resulting condensed constituents from the residue gas, processing the resulting condensed constituents to obtain a relatively heavy liquid hydrocarbon fraction for forming said contacting liquid, and conveying said heavy liquid fraction to the place of contact.

5. The method of recovering desirable liquefiable constituents from a distillate gas mixture having an initial pressure at least as high as a pressure within the retrograde condensation range of said mixture, which comprises contacting the distillate gas mixture with a heavy liquid hydrocarbon fraction for forming a mixture having a higher normal condensation pressure than the original gas mixture to condense said liquefiable constituents from the gas mixture, contacting the residual gas with a relatively heavy liquid hydro-

carbon fraction to absorb portions of the desirable hydrocarbons which remain in the vapor phase at said pressure, separating the resulting condensed constituents from the residual gas, processing the condensed constituents to obtain the relatively heavy liquid fraction for forming said contacting liquids, and conveying said heavy liquid fraction to the places of contact.

6. The method of recovering desirable liquefiable constituents from a distillate gas mixture having an initial pressure at least as high as a pressure within the retrograde condensation range of said mixture, which comprises contacting the distillate gas mixture while at said pressure with a heavy liquid hydrocarbon fraction for forming a mixture having a higher normal condensation pressure than the original gas mixture to condense said liquefiable constituents from the gas mixture, separating the resulting condensed constituents from the residual gas, contacting the residual gas with relatively heavy liquid hydrocarbon fractions to absorb portions of the desirable liquefiable constituents which remain in the vapor phase at said higher condensation pressure of said mixture, processing said liquids to obtain the heavy liquid hydrocarbon fraction for forming said contacting liquid, cooling the heavy liquid hydrocarbon fraction, and conveying said cooled heavy liquid hydrocarbon fraction to the places of contact.

7. The method of recovering desirable liquefiable constituents from distillate well gas initially at a pressure at least as high as a pressure within the retrograde condensation range of said constituents which comprises, expanding the gas to a pressure within the retrograde condensation range of said constituents, separating the result-

5 ing condensed constituents from the uncondensed gas, fractionating said condensed constituents into a relatively low boiling gasoline fraction and a relatively heavy liquid fraction, contacting the expanding gas with at least a portion of said relatively heavy liquid fraction and thereby raising the normal condensation pressure of said constituents, and contacting the uncondensed gas with another portion of said heavy liquid fraction to absorb portions of desirable liquefiable constituents remaining in vapor phase at said higher condensation pressure.
